SOUND RECORDING APPARATUS

Arthur G. Zimmerman, Indianapolis, Ind., assignor to Radio Corporation of America, a corporation of Delaware

Application December 29, 1938, Serial No. 248,250

1 Claim. (Cl. 88—23)

This invention relates to sound recording apparatus, and more particularly to apparatus for photographically recording sound on film. The particular feature involved is a novel attachment for commercial sound recording systems which will indicate at any time the effective brightness of the recording light.

In the recording systems heretofore used which included either a galvanometer or light valve for modulating the light beam, it has been customary to use a high intensity incandescent lamp as the light source. These incandescent lamps have a normal life of the order of fifty hours, and the brightness thereof changes during their life. In order to maintain the light constant during the recording of a given section of film, it has been customary to provide an ammeter in series with the lamp and to maintain the current through the lamp at a constant value. This has not been sufficient to maintain the lamp at perfectly uniform brightness, as the tungsten which evaporates from the lamp filament is deposited on the glass envelope and some times absorbs a very considerable portion of the light. The amount of filament material deposited in a given location on the lamp envelope varies from lamp to lamp and is not predictable, so that, with a given change in the electrical characteristics of the filament, a corresponding change in the brightness of the lamp did not always follow.

In the apparatus of the present invention, an appropriate photometer is attached to and interconnected with the mechanism of the optical system so that at any time during intervals between actual sound records the brightness of the lamp emitted by the lamp may be conveniently and rapidly measured.

One object of the invention is to provide an improved photometer for measuring the brightness of incandescent lamps.

Another object of the invention is to provide an improved photometric attachment for phonographic recorders.

Another object of the invention is to provide a photometric device which may be attached to standard commercial recording optical systems and which will permit substantially instantaneous readings of the recording lamp brightness.

Other and incidental objects of my invention will be apparent to those skilled in the art from a reading of the following specification and an inspection of the accompanying drawings in which

Figure 1 is a top view of a commercial record-

ing optical system with my photometric attachment applied thereto and with the cover removed, and

Figure 2 is a side view taken from the bottom of Fig. 1 and showing the same type of optical system with a portion of the casing broken away.

The recording optical system shown in the drawings is of the commercial type generally known as the RCA Photophone recording system, and the optical elements thereof, as well as the operation of the system in producing various types of sound track, are described in detail in an article appearing on pages 258 to 273 of the Journal of the Society of Motion Picture Engineers for September 1937. These details are, in general, immaterial to the present invention and only such of them as are directly pertinent are specifically referred to hereinafter.

In the optical system, an exciter lamp indicated at 11 is provided in a light-tight casing 10. Light from this exciter lamp passes through the housing 12 which may enclose lenses, diaphragms, ground noise reduction shutters, etc., to the condenser lens 13, which directs the light to the mirror of the galvanometer 14. Light is reflected by the galvanometer to a second housing or tube indicated at 15 which carries a narrow slit adjacent the end thereof generally indicated at 16 and at the other end carries an objective 17 which serves to focus the recording light upon the film 28 at the recording point. Within the beam of light, but below the portion thereof which passes the slit, there is provided a mirror 18 which directs a portion of the light to an appropriate monitoring apparatus such, for example, as that described and claimed in Sachtleben Patent No. 2,206,645, issued July 2, 1940.

A second mirror 19 is provided which is movable in a plane closely adjacent the slit of the recording system. This mirror 19 is mounted upon a shaft 20 which is rotatable in an appropriate bearing formed in the casing 24 of the apparatus. The mirror 19 may either be a glass mirror or it may be an appropriate plated metal surface, in either case being attached by the arm 21 to the shaft 20. This arm 21, as shown in both figures of the drawings, has an enlarged cylindrical portion which fits over the shaft 20 and which carries on its external surface the spring 22, which rotates the mirror downwardly out of the light beam.

At the opposite end of the shaft 20 there is attached a handle 23 for rotating the shaft 20 and

with it the mirror 19. As the handle 23 is pressed downwardly, the mirror 19 is raised into operative position between the galvanometer mirror and the entrance pupil of the tube 15 which, as before stated, may be a slit. The mirror 19 thereby intercepts the portion of the light beam which would otherwise reach the film 28 and deflects the light from a horizontal direction to a vertical direction. The beam, when directed vertically, strikes the photoelectric cell 25, which is preferably of the photronic or other similar type which generates a current, depending upon the amount of light incident thereon. The current produced by the cell 25 is carried to the meter 26 by the leads 27. The meter 26 may, as shown in the drawings, be mounted on the side of the case 24 or it may be mounted in any other convenient location.

It will be apparent that when the handle 23 is depressed to bring the mirror 19 into operative position the current through the exciter lamp

11 may be adjusted to give a predetermined reading on the meter 26, and the exposure of the sound record film may thereby be maintained constant. This operation can be performed quite rapidly and may even be accomplished during the momentary pause between the speech of different actors or in similar short pauses during the recording operation.

Having now described my invention, I claim:

In combination, a sound recording optical system having a light source and means for directing light from said source in a beam along a predetermined path, photoelectric means adjacent said path, light-intensity indicating means connected to said photoelectric means, light reflecting means, and rotary means movable about an axis parallel to said path for moving said light reflecting means into the path of the said light beam for reflecting the light of said beam to said photoelectric means.

ARTHUR G. ZIMMERMAN.
